HAT LINING

Morris E. Cohen, New York, N. Y., assignor of one-half to The L. H. Bandeau Co., a partnership composed of Louis Hoffeld, New York, N. Y., and Gaule Hoffeld, Brooklyn, N. Y.

Application May 28, 1932. Serial No. 614,115

4 Claims. (Cl. 2—190)

This invention relates to new and useful improvements in hat linings and has more particular reference to a lining intended particularly for ladies', men's and children's hats.

5 The invention has for an object the construction of a lining which has numerous advantages over the present types of linings and which overcomes various defects inherent in linings now in use.

10 The invention proposes particularly to construct a lining which is characterized by a substantially dome shaped material of one piece for extending across the inner top and sides of a hat and having a flat top and curved sides, and a strip of material attached upon the bottom edge of said dome shaped material for extending around the inner sides of the hat in cylindrical form.

15 It is old to manufacture linings from various pieces secured together and also old to manufacture a lining from one piece of material. It is particularly pointed out that the invention covers a lining made from a dome shaped portion and a band portion arranged in a certain manner so as to gain numerous advantages.

20 A popular type of lining at the present time is a two piece lining in which there is a substantially circular tip at the top and a very wide band around the sides, and bent over at the top and sewed upon the edges of said tip. This type of lining has a great disadvantage especially when applied to hats which must be blocked in that impressions of the seams at the top are transferred to the hat during blocking. This 25 disadvantage is overcome in the instant invention whereby the seam occurs at the sides of the hat, which is not subjected to great pressure during the blocking, as the top is.

30 For similar reasons as pointed out in the previous paragraph, the invention lining is superior to linings which are composed of one piece but formed with a plurality of seams or pleats at the top in the construction of the lining into the proper shape.

35 Another very important advantage gained by the lining according to this invention is that it may be produced by a process which is far superior and capable of cheaper use when compared with processes used in the construction of present day linings.

40 According to the new process the lining is manufactured by placing a strip of material within the periphery of and with its outer edge upon the outer edge of a substantially circular piece of material, and then sewing down one end

of the edge of the strip to the edge of the circular piece and continuing sewing of the strip around the edge of the circular piece, but pleating the edge of the circular piece during the sewing and finally when the strip is completely attached around the circular piece continue the sewing transversely across the strip for securing together the ends of the strip. Thus, the complete lining is constructed with one continuous line of stitches.

The invention still further proposes the construction of an article of the class mentioned which is simple and which may be manufactured and sold at a very cheap cost.

45 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a hat lining constructed according to this invention.

Fig. 2 is a transverse sectional view of the lining shown in Fig. 1.

Fig. 3 is a fragmentary sectional view taken on the line 3—3 of Fig. 1.

The hat lining according to this invention 50 comprises a substantially dome shaped piece of material 10 for extending across the inner top and sides of a hat and having a substantially flat top 11 and curved sides 12. A band of material 13 is attached along the bottom edge of said dome shaped material 10 and is for the purpose of extending around the sides of the hat in cylindrical fashion so that the lower edge may be bent up and secured within the hat to mount the lining in the hat.

The dome shaped piece of material 10 is made from a substantially circular piece, and is formed into the dome shape by forming a plurality of pleats 14 along its edge during the securing of the strip 13 in place. The strip 13 has its ends 15 stitched together. These ends are cut at an inclination as plainly shown in Fig. 1 so that the ends may be secured together by continuing the sewing which attaches the strip 13 to the dome shaped material 10 as hereinafter further described.

The process for manufacturing the lining comprises pleating or gathering the bottom edge of the dome shaped piece 10 and simultaneously sewing it upon the top edge of the strip of material 13 and after the strip is completely sewn around

the edge of the dome shaped material, continuing the sewing transversely across the strip 13 so as to sew the ends of the strip together. It is advisable that the strip 13 during its attachment 5 upon the dome shaped material should be disposed within the dome shaped material as indicated by the dot and dash lines 16 in Fig. 2. Then after it is secured in place by stitches 17 it should be moved out as shown in full lines in 10 Fig. 2. The bottom edge should be turned outwards as indicated by the dot and dash lines 18 when the lining is attached within a hat. The bent top edge indicated by reference numeral 15 19 of the strip 13 serves as a guard to prevent injury to the pleats of the dome shaped piece when a hat provided with the lining is placed upon one's head. If the edges of the dome shaped piece were not disposed below bend 19 or if the dome shaped piece 12 were bent up instead of 20 the upper edge of the strip 13 bent down, then there would be a strain upon the seam when the hat is placed on one's head.

The details of attaching the strip 13 upon the dome shaped piece may be understood by first noticing that the ends of the strip 13 are cut at 25 an inclination so that there is an acute corner 20 and an obtuse corner 21. The acute corner 20 should first be attached upon the edge of the dome shaped piece of material 10 at the point 30 22, then the stitches 17 should be applied to secure the strip 13 upon the edge of the piece 10, pleating and gathering the edge of the piece 10 through this operation until the strip 13 is 35 completely attached around the edge of the dome shaped material, then the stitches 17 should bend off at an angle at the point 23 and the ends of the strip 13 seamed together.

While I have illustrated and described my invention with some degree of particularity, I realize that in practice various alterations therein 40 may be made. I therefore reserve the right and privilege of changing of the form of the details of construction or otherwise altering the arrangement of the correlated parts without departing 45 from the spirit or the scope of the appended claims.

Having thus described my invention, what I claim as new, and desire to secure by United States Letters Patent is:—

50 1. A process for manufacturing a hat lining, consisting of placing a strip of material within the periphery of and with its edge upon the outer edge of a substantially circular piece of material, sewing one end of the edge of said strip 55 to the edge of said circular piece, continuing to sew the strip to the circular piece, but pleating the edge of the circular piece, during the sewing,

and continuing the sewing between the ends of the strip to join these ends together after the strip is sewn completely around said circular piece.

2. A process for manufacturing a hat lining, 80 consisting of placing a strip of material within the periphery of and with its edge upon the outer edge of a substantially circular piece of material, sewing one end of the edge of said strip to the edge of said circular piece, continuing to sew the strip to the circular piece, but pleating the edge of the circular piece, during the sewing, and continuing the sewing between the ends of the strip to join these ends together after the strip is sewn completely around said circular piece, said strip 85 having one end cut at an acute angle and the other end at an obtuse angle, and the acute end being first secured upon the edge of the circular piece to allow a continuation of the stitching, 90 after the strip has been completely attached upon the edge of the circular piece so that the stitching continues along the obtuse angle and so secures the ends of strip together.

3. A process for manufacturing a hat lining, 100 consisting of placing a strip of material within the periphery of and with its edge upon the outer edge of a substantially circular piece of material, sewing one end of the edge of said strip to the edge of said circular piece, continuing to sew the strip to the circular piece, but pleating the edge 105 of the circular piece, during the sewing, and continuing the sewing between the ends of the strip to join these ends together after the strip is sewn completely around said circular piece, said strip 110 having one end cut at an acute angle and the other end at an obtuse angle, and the acute end being first secured upon the edge of the circular piece to allow a continuation of the stitching, 115 after the strip has been completely attached upon the edge of the circular piece so that the stitching continues along the obtuse angle and so secures the ends of strip together, the strip of material 120 being moved out from within the circular piece of material after it has been completely secured around the edge of the circular piece of material, and the ends of the strip being stitched together in the latter mentioned position.

4. A process for manufacturing a hat lining, 125 consisting of placing a strip of material within the periphery of and with its edge upon the outer edge of a substantially circular piece of material, sewing one end of the edge of said strip to the edge of said circular piece, and continuing to sew the strip to the circular piece but pleating the 130 edge of the circular piece during the sewing.

MORRIS E. COHEN.
